UNITED STATES PATENT OFFICE.

LARS O. GRONDAHL, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING SYSTEM.

Application filed April 16, 1921. Serial No. 461,781.

To all whom it may concern:

Be it known that I, LARS O. GRONDAHL, a citizen of the United States, residing at Pittsburgh, in the county of Allegheny and State of Pennsylvania, have invented certain new and useful Improvements in Railway Signaling Systems, of which the following is a specification.

My invention relates to railway signaling, and is particularly well adapted to signaling systems of the type wherein roadside signals are governed by track circuits which in turn are influenced by the passage of cars or trains along the track.

I will describe several forms of signaling apparatus embodying my invention, and will then point out the novel features thereof in claims.

In the accompanying drawings, Fig. 1 is a diagrammatic view showing one form of signaling apparatus embodying my invention. Fig. 2 is a diagrammatic view showing another form of apparatus embodying my invention, and which may be used when three-indication signals are desired. Fig. 3 is a view showing a modification of the apparatus shown in Fig. 2 and also embodying my invention.

Similar reference characters refer to similar parts in each of the several views.

Referring first to Fig. 1, the reference characters E and E^a, designate the track rails of a railway over which traffic normally moves in the direction indicated by the arrow, and which rails are divided by insulated joints 2 to form a track section A—B. Although I have herein shown only one such section, it is understood that a complete signaling system embodying my invention will usually comprise a series of sections similar to the one shown in the drawing and each provided with the apparatus which I have shown for section A—B.

The track section A—B is provided with a track circuit comprising a source of current connected across the rails adjacent the exit end of the section and an electric lamp L connected across the rails adjacent the entrance end of the section. As here shown, the source of current for this track circuit is the secondary winding 6 of a transformer T^a, the primary of which is connected with a transmission line 3 to which alternating

signaling current is constantly supplied by a generator 4. The lamp L, as here shown, is of the incandescent type, although I do not desire to be limited to a lamp of this specific kind. The parts of the track circuit are so adjusted that the lamp L is lighted when the track section is unoccupied, but is dark when the section is occupied by a car or train.

Located adjacent the entrance end of the section A—B is a signal S comprising, as here shown, two electric lamps R and G, arranged to indicate "stop" and "proceed," respectively, when lighted. These lamps are connected in multiple across the terminals of the secondary 6 of the transformer T^b, the primary of which is constantly supplied with signaling current from the transmission line 3. A fixed resistance 7 is preferably included in the connection between each lamp and one terminal of the secondary 6. The branch including the stop lamp R is provided with another fixed resistance 8, and the branch including the proceed lamp G is provided with a light responsive cell P which is so located as to be exposed to the light emitted by the track circuit lamp L. The cell P has the characteristic that its electrical resistance varies with changes in the intensity of the light to which it is exposed. A cell having this characteristic may be made, for example, of selenium, stibnite or copper oxide, or it may be what is known as a photo-electric cell in which the active material is an alkali metal. This cell should be so located as to receive light from the lamp L but not from any other source. On account of the low current carrying capacity and high resistance of light sensitive cells it may be necessary to place cell P in circuit with the high voltage primary of a transformer the low voltage secondary of which will then supply current to lamp G.

It will be seen from the foregoing that the electrical resistance of the cell P is comparatively high when the lamp L is extinguished, and comparatively low when this lamp is lighted. The circuits for the signal lamps R and G are so adjusted that when the lamp L is extinguished the voltage across lamp G is below the value required to light this lamp, and the voltage across lamp R is above the value required to pro-

duce luminosity; whereas when lamp L is illuminated so that the resistance of cell P is reduced, the voltage across lamp G becomes sufficient to illuminate this lamp, and the voltage across lamp R is then decreased to such value that this lamp is dark. It follows, therefore, that when the track section $A-B$ is occupied by a car or train, lamp R is illuminated and lamp G is dark, so that signal S indicates stop; and that when the track section is unoccupied lamp G is illuminated and lamp R is extinguished so that the signal indicates proceed.

It will be observed that if the track circuit lamp L should burn out or should become extinguished for any reason other than the occupancy of track section $A-B$ by a car or train, the resistance of cell P will be high, so that signal S will indicate stop.

Referring now to Fig. 2, I have shown a plurality of successive track sections $A-B$, $B-C$, and $C-D$, which sections are electrically separated by insulated joints. Each section is provided with a track circuit which is the same as that shown in Fig. 1, that is, each track circuit includes the secondary 5 of the transformer T at the exit end of the section and an incandescent lamp at the entrance end of the section designated by the reference character L with a suitable exponent. Located adjacent the entrance end of each section is a signal designated S with a suitable exponent, and each of which signals comprises three electric lamps R , Y and G , adapted to indicate "stop," "caution" and "proceed," respectively, when lighted. Located adjacent each signal are four light responsive cells designated P^1 , P^2 , P^3 and P^4 , these reference characters being provided with subscripts corresponding to the location of the cells. The four cells at each signal are exposed to light from the adjacent track circuit lamp L but are so protected that they do not receive light from any other source.

Referring specifically to signal S^c , the stop lamp R is controlled by a Wheatstone bridge device H^c , which is connected across the terminals of secondary 6 of the adjacent transformer T^c by wires 18 and 22. The two upper arms of this bridge are formed by the cell P^4c and a fixed resistance 9, while the two lower arms are formed by a fixed resistance 10 and the cell P^3c . The connecting member of the bridge comprises the primary of a transformer 11, the secondary of which is connected with lamp R of signal S^c , through wires 12, 13, 14 and 15. The bridge H^c is so adjusted that when the light responsive cells P^4c and P^3c are illuminated by track circuit lamp L^c , no voltage is impressed on the primary of transformer 11, so that lamp R of signal S^c is dark. In other words when lamp L^c is illuminated, the bridge H^c is balanced, so that no current

flows in the connecting member. When lamp L^c is extinguished, however, the balance of the bridge H^c is upset, so that current flows in the primary of transformer 11, and the voltage induced in the secondary of this transformer is then sufficient to illuminate the stop lamp R of signal S^c .

The caution lamp Y of signal S^c is connected with the secondary of transformer 11 at signal S^b , the circuit being through wires 12, 16, 17 and 15. Lamp Y of signal S^c is therefore connected in multiple with the stop lamp R at signal S^b , and is illuminated or extinguished according as lamp R of signal S^b is illuminated or extinguished.

The proceed lamp G of signal S^c is included in a circuit which receives energy from the secondary 6 of transformer T^b , this circuit being from left-hand terminal of secondary 6, through wires 18 and 19, light responsive cell P^2b , wire 20, light responsive cell P^1c , lamp G , and wires 21 and 22 to the right-hand terminal of secondary 6. Cell P^2b is exposed to the light from track circuit lamp L^b , while cell P^1c is exposed to light from lamp L^c . This circuit is so adjusted that lamp G is illuminated when both of the light responsive cells are exposed to light, but is extinguished when either or both of these cells are dark. As in Fig. 1, the cells P^2b and P^1c may be in the primary circuit of a transformer, the secondary of which supplies current to lamp G .

The circuits for the lamps of each signal are similar to those for the lamps of signal S^c .

As shown in the drawing, track section $A-B$ is occupied by a car or train W , so that lamp L^b is extinguished. Cell P^1b is therefore dark, so that lamp G of signal S^b is extinguished. Lamp Y of this same signal is extinguished, because the Wheatstone bridge device H^a is balanced. Lamp R of signal S^b is lighted, however, because the Wheatstone bridge device H^b is unbalanced. It follows, therefore, that signal S^b indicates stop. In signal S^c , the proceed lamp G is extinguished because cell P^2b does not receive light. The caution lamp Y of signal S^c is lighted, however, because the bridge device H^b is unbalanced. The stop lamp R of signal S^c is extinguished, because the bridge device H^c is balanced. Signal S^c , therefore, indicates caution. As for signal S^d , the proceed lamp G is illuminated because the light responsive cells in the circuit for this lamp receive light from the corresponding track circuit lamps. Lamp Y is extinguished because the bridge device H^c is balanced, and lamp R is extinguished because the bridge device H^d is balanced. It follows therefore that signal S^d indicates proceed.

Referring now to Fig. 3, the track circuits and the signals are the same as in Fig. 2, but

the control of the signal lamps is somewhat different.

In Fig. 3 each signal is provided with an auxiliary controlling lamp designated K with an exponent corresponding to the location, which lamp is controlled by the track circuit lamp for the section next in advance. Considering the auxiliary lamp K^c for signal S^c, the circuit for this lamp is from secondary 23 of transformer T^B, through wire 24, light responsive cell P², wire 25, lamp K^c, and wire 26 to secondary 23. The cell P² is exposed to light from the track circuit lamp L^B, and the circuit is so adjusted that when lamp L^B is extinguished lamp K^c is likewise extinguished, and that when lamp L^B is lighted lamp K^c is also lighted. Lamp K^c constitutes, then, in effect, a repeater at location C for the lamp L^B at location B. To get proper current values a transformer may be interposed between cell P²_B and lamp K^c.

Each of the signals is controlled by a number of light responsive cells designated P¹, P², P³, P⁴, P⁵, and by two other light responsive cells designated Q¹ and Q². Each cell P is exposed to light from the adjacent track circuit lamp L, while each cell Q is exposed to light from the adjacent repeater lamp K, as indicated by the dotted lines in the drawing. These cells are so enclosed and protected that no light rays can reach them other than from the sources just mentioned.

Considering signal S^B, for example, the stop lamp R is controlled in the same manner as in Fig. 2; that is, this lamp is connected with the secondary of a transformer 11, the primary of which constitutes the connecting member of the Wheatstone bridge device H^B. It follows, therefore, that this lamp is illuminated when section A—B is occupied, but is extinguished at all other times.

The circuit for the proceed lamp G is from the lefthand terminal of secondary 6 of transformer T^B, through wires 18, 28 and 29, lamp G, wire 30, cell P¹, cell Q¹, and wires 31, 32 and 22 to secondary 6. The parts of this circuit are so adjusted that lamp G is illuminated when cells P¹ and Q¹ receive light from lamps L^B and K^B, respectively, but that it is extinguished when either or both of the cells P¹ and Q¹ are dark. A transformer may be placed in circuit between the light sensitive cells and lamp G.

The caution lamp Y of signal S^B is controlled as follows: Bridged across the terminals of secondary 6 of transformer T^B are a light-responsive cell Q² and a resistance 27, these two elements being in series, and as hereinbefore stated the cell Q² is exposed to light from the repeater lamp K^B. The lamp Y is provided with a circuit which

passes from secondary 33 of transformer T^B through wire 34, cell P⁵, lamp Y, wire 35, cell Q² and wire 36 to secondary 33. The parts of this circuit are so adjusted that when cells P⁵ and Q² are both exposed to light the potential across cell Q² due to secondary 6 is equal and opposite to the potential across this cell due to secondary 33, so that no current flows in the circuit and the lamp Y is consequently extinguished. When cell P⁵ receives no light, the resistance of the circuit including lamp Y is so high that this lamp is then extinguished regardless of the condition of cell Q. When cell Q² receives no light, however, and cell P⁵ receives light from lamp L^B, the potentials across cell Q² and cell P⁵ are no longer equal and sufficient current then flows in the circuit of lamp Y to light this lamp. An additional transformer may be interposed between the light sensitive cells and lamp Y.

As shown in the drawing, track section A—B is occupied by a car or train W, so that track circuit lamp L^B for this section is extinguished. Cell P¹ at location B is consequently dark, so that lamp G of signal S^B is extinguished. Cell P⁵ at this same location is dark, so that lamp Y is extinguished. The bridge device H^B is unbalanced, however, so that lamp R is lighted, and, consequently, signal S^B indicates stop.

At signal S^B, the repeater lamp K^c is dark, because track circuit lamp L^B is extinguished. Cell Q¹ is dark, so that lamp G is extinguished. Cell Q² is dark, but cell P⁵ receives light from lamp L^C, and so the caution lamp Y is lighted. The stop lamp R is dark, because the bridge device H^C is balanced. It follows, therefore, that signal S^B indicates caution.

At signal S^D, cells P¹ and Q¹ are both illuminated, so that the proceed lamp G is lighted. The potentials across cell Q² are balanced, so that lamp Y is extinguished, and the Wheatstone bridge device H^D is balanced so that the stop lamp R is extinguished. It follows, therefore, that signal S^D indicates proceed.

Although I have herein shown and described only three forms of apparatus embodying my invention, it is understood that various changes and modifications may be made therein within the scope of the appended claims without departing from the spirit and scope of my invention.

Having thus described my invention, what I claim is:

1. In combination, a track circuit comprising the track rails of a railway, a source of current and a lamp; a light-responsive cell located in the trackway and subjected to rays from said lamp, and a railway signal located in the trackway and controlled by said cell.

2. A railway signaling system comprising a track circuit including a lamp, a light-responsive cell located in the trackway and controlled by rays from said lamp, and a signal located in the trackway and controlled by said light-responsive cell.
3. In combination, a railway track, a lamp, means controlled by trains passing along the track for lighting and extinguishing said lamp, a light-responsive cell in the trackway subjected to rays from said lamp, and a trackway signal controlled by said cell.
4. In combination, a track circuit comprising track rails, a source of current and a lamp; a cell located in the trackway and exposed to light from said lamp and adapted to vary in electrical resistance according to the intensity of the light which it receives, and a railway signal located in the trackway and controlled by said cell.
5. In combination, a section of railway track; a track circuit including the rails of said section, a source of current and a lamp; a light-responsive cell located in the trackway and affected by the light rays emitted by said lamp, and a signal located in the trackway and controlled by said cell.
6. In combination, a track circuit comprising track rails, a source of current and a lamp; a cell located in the trackway and exposed to light from said lamp and adapted to vary in electrical resistance according to the intensity of the light which it receives, a signal circuit including said cell and a source of current, and a trackway signal included in said signal circuit and responsive to the variation in the resistance of the signal circuit caused by lighting and extinguishing said lamp.
7. In combination, a track circuit comprising track rails, a source of current and a lamp; a cell located in the trackway and exposed to light from said lamp and adapted to vary in electrical resistance according to the intensity of the light which it receives, a signal circuit including a source of current and said cell, and a trackway signal governed by said circuit and arranged to give a proceed indication when said lamp is lighted and a stop indication when the lamp is extinguished.
8. In combination, a railway track, a lamp, means controlled by trains passing along said track for varying the voltage applied to said lamp, a light-responsive cell located in the trackway and exposed to light rays from said lamp, and traffic governing means in the trackway controlled by said cell.
9. In combination, a railway track divided into sections, a track circuit for each section including a source of current and a light-emitting device, light-responsive cells exposed to the rays from said light-emitting devices, signals for the sections each adapted to indicate stop, caution and proceed, and circuits for said signals controlled by said cells.
10. In combination, a railway track, a lamp, means controlled by trains passing along said track for varying the voltage applied to said lamp, and traffic governing means located in the trackway and controlled by the light rays emitted by said lamp.
11. In combination, a railway track divided into sections, a track circuit for each section including a source of current and a light-emitting device, a repeating light-emitting device for each section included in circuit with a source of current and a light-responsive cell exposed to the track circuit device for the section next in advance, a signal for each section adapted to indicate proceed, caution and stop, and means for causing each signal to indicate proceed when both light-emitting devices for the section are lighted, caution when the track circuit device is lighted and the repeating device is dark, and stop when both devices for the section are dark.
12. In combination, a track circuit including the rails of a railway track and an electric lamp, and railway traffic governing apparatus located in the trackway and controlled by the light emitted by said lamp.
13. In combination, a track circuit including an electric lamp, and a railway signal located in the trackway and controlled by said lamp.
14. In combination, a railway track divided into a plurality of sections, a track circuit for each section including a lamp, a repeating lamp for each section controlled by the track circuit for the section next in advance, and traffic governing means controlled by said lamps.
15. In combination, a railway track divided into a plurality of sections, a track circuit for each section including a lamp, a repeating lamp for each section controlled by the track circuit for the section next in advance, and signals for said sections controlled by said lamps.
16. In combination, a railway track divided into sections, a main lamp for each section, means responsive to a train in each section for controlling the lighting of the main lamp for such section, a repeating lamp for each section controlled by the main lamp for the section next in advance, and traffic governing means controlled by said lamps.
17. In combination, a railway track divided into sections, a main lamp for each section, means responsive to a train in each section for controlling the lighting of the main lamp for such section, a repeating lamp for each section controlled by the main

lamp for the section next in advance, and signals for the sections controlled by said lamps.

18. In combination, a railway track, a plurality of main electric lamps, means controlled by trains passing over said track for varying the voltage applied to said lamps, auxiliary lamps for repeating the variations in illumination of said main lamps, and traffic governing means controlled by said lamps.

19. In combination, a railway track divided into sections, a track circuit for each section including a lamp, a repeating lamp for each section controlled by the track circuit lamp for an advance section, a signal for each section, and a controlling circuit for each signal including a light-responsive cell exposed to the track circuit lamp for the associated section and a light-responsive cell exposed to the repeating lamp for the same section.

20. In combination, a railway track divided into sections, a track circuit for each section including a lamp, a repeating lamp for each section controlled by the track circuit lamp for an advance section, a signal for each section, and a controlling circuit for each signal including two light-responsive cells in series exposed respectively to the two lamps associated with such section.

21. In combination, a railway track divided into sections, a track circuit for each section including a lamp, a repeating lamp for each section controlled by the track circuit lamp for an advance section, a signal for each section, a controlling circuit for each signal including a source of current and a light-responsive cell exposed to the track circuit lamp for the associated section, and means governed by the repeating lamp for the associated section and operating when such lamp is lighted to introduce an equal and opposite source of current into said controlling circuit.

22. In combination, a railway track divided into sections, a track circuit for each section including a lamp, a repeating lamp for each section controlled by the track circuit lamp for an advance section, a signal for each section, a controlling circuit for each signal including two sources of current, and means for governing the supply of current from said two sources by the two lamps associated with such section.

23. In combination, a railway track divided into sections, a track circuit for each section including a lamp, a repeating lamp for each section controlled by the track circuit lamp for an advance section, a signal for each section, a controlling circuit for each signal including two opposing sources of current, and means for governing the supply of current from said two sources by the two lamps associated with such section.

24. In combination, a railway track divided into sections, a track circuit for each section including a lamp, a repeating lamp for each section controlled by the track circuit lamp for an advance section, a signal for each section, a controlling circuit for each signal including in series a source of current and a light-responsive cell exposed to the associated track circuit lamp and a light-responsive cell exposed to the associated repeating lamp, and another source of current connected across the second of said cells.

25. Railway traffic controlling apparatus comprising a lamp located in the trackway and controlled by the passage of cars or trains, a Wheatstone bridge controlled by said lamp, and traffic governing means controlled by said Wheatstone bridge.

26. Railway traffic controlling apparatus comprising a lamp located in the trackway and controlled by the passage of cars or trains, a Wheatstone bridge connected across a source of current, two opposing legs of such bridge including resistances and the other two opposing legs including light-responsive cells exposed to light from said lamp, the bridge member of said bridge including the primary of a transformer, and a signal controlled by the secondary of said transformer.

27. Railway traffic controlling apparatus comprising a lamp located in the trackway and controlled by the passage of cars or trains, a Wheatstone bridge having light-responsive cells in opposite legs exposed to said lamp, and traffic governing means controlled by the bridge member of said bridge.

28. Railway traffic controlling apparatus comprising a Wheatstone bridge, means located in the trackway for controlling the resistance of at least one leg of said bridge in accordance with the presence and absence of trains, a transformer the primary of which constitutes the bridge member of said bridge, and traffic governing means controlled by the secondary of said transformer.

29. In combination, a railway track divided into sections, a track circuit for each section including a lamp, a repeating lamp for each section controlled by the track circuit lamp for an advance section, a signal for each section, and a controlling circuit for each signal including a proceed circuit for each signal including two light-responsive cells exposed respectively to the two lamps for the associated section, a caution circuit for each signal including two sources of current, a light-responsive cell associated with each source and exposed to the track circuit lamp and the repeating lamp respectfully for the corresponding section, a Wheatstone bridge for each section connected across a source of current and including light-responsive cells exposed to the

track circuit lamp for the associated section, and a stop lamp for each section controlled by the bridge member of the associated bridge.

5. 30. In combination, a section of railway track, a light-responsive cell located in the trackway, a lamp also located in the trackway for illuminating said cell, a circuit for said lamp controlled by the presence and absence of trains in said section, and a trackway signal controlled by said cell.

15. 31. In combination, a section of railway track, a light-responsive cell located in the trackway, a lamp also located in the trackway for illuminating said cell, a track circuit including the rails of said section for controlling said lamp, and a trackway signal controlled by said cell.

20. 32. The method of governing railway traffic which consists in controlling the lighting of a lamp according to traffic conditions, supplying light from said lamp to a light-responsive cell located in the trackway, and controlling a trackway traffic governing device by said cell.

25. 33. The method of governing railway traffic which consists in supplying light to a light-responsive cell located in the trackway

from an electric lamp also located in the trackway, and controlling the circuit for 30 said lamp in accordance with traffic conditions.

34. The method of governing railway traffic which consists in supplying light to a light-responsive cell located in the trackway from an electric lamp also located in the trackway, and varying the voltage applied to said lamp according to traffic conditions.

35. 35. In combination, a section of railway track, a light-responsive cell and a source of light, both located in the trackway, means including a track circuit for said section for controlling the illumination of said cell by said source, and trackway signaling means controlled by said cell.

40. 36. In combination, a section of railway track, a light-responsive cell and a source of light both located in the trackway, means located entirely in the trackway and governed by the presence and absence of trains 50 in said section for controlling the illumination of said cell by said source, and signaling means controlled by said cell.

45. In testimony whereof I affix my signature.

LARS O. GRONDAHL.
